UNITED STATES PATENT OFFICE

GEORGE E. WARREN, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY

SEWING MACHINE

Application filed December 14, 1922. Serial No. 606,918.

The present invention relates to hook needle lockstitch sewing machines and is intended primarily as an improvement in lock-stitch sewing machines of the so-called "McKay type", although the invention is not limited to use in machines of this type.

In McKay sewing machines in which the shoe is supported by a horn which extends inside of the shoe it has been found to be impracticable to use a thread arm or thread measuring device to supply thread for one side of the needle loop as the needle retracts through the work. Consequently, heretofore it has been the practice in this type of lock-stitch machines, where a take-up has been employed to set the stitch, to use an extremely large needle as compared to the size of the thread so as to permit the thread to reeve through the hook of the needle.

In machines of this type in which a take-up is not employed to set the stitch it has heretofore been the practice to utilize the shuttle to set the stitch, the thread for the work side of the needle loop, as the needle retracts through the work, being supplied from the preceding needle loop which is subsequently drawn down into its final position in the seam by the action of the shuttle. In these machines the stitch is set against a thread lock and where the shuttle has been utilized to set the stitch it has been the practice to open the thread lock during the passage of the needle loop over the shuttle so as to permit the shuttle, after setting the stitch, to draw thread from the supply for use in making the next stitch. The use of a large needle is objectionable for obvious reasons and when the shuttle is utilized both to pull off thread from the supply and to set the stitch the position of the lock of the stitch in the work is irregular and also there is liability of injury to the thread by the action thereon of the thread lock as it is opened while the thread is under the stitch setting strain tending to pull the thread through the lock.

To eliminate the objectionable features of prior hook needle lockstitch machines which are not provided with a thread arm or equivalent thread measuring device and to provide

a machine of this class which will operate to sew a seam of stitches which are disposed accurately and uniformly in the work and without liability of breakage or injury to the thread the present invention contemplates the provision in a machine of this class of thread handling devices constructed and arranged to cooperate in such a manner as to permit the stitch to be set by the needle. By utilizing the needle to set the stitch the thread lock can be opened and closed at points in the cycle where there is substantially no strain upon the thread tending to pull it through the lock so that any liability of injury to the thread is eliminated and also an accurate and uniform manipulation of the thread is insured so that the locks of the stitches are uniformly located with relation to the surface of the work.

To permit the stitch to be set by the needle it is necessary to provide means other than the needle for shortening the preceding loop after it has been passed about the shuttle and, accordingly, a machine embodying the present invention will comprise a take-up which acts to pull the needle loop from the shuttle partially back through the work. A feature of the present invention contemplates the provision of means controlled by the thickness of the work for determining the position of the lock of the stitch with relation to the surface of the work in order to adapt the machine for operation upon work of varying thickness or upon different thicknesses of work. The position of the lock is preferably controlled by maintaining constant the length of loop left on the needle side of the work by the take-up and in the preferred embodiment of the invention hereinafter described this result is secured by varying the operation of the take-up. During each cycle of the machine the required amount of thread may be drawn from the supply by any suitable means, but it is preferred to utilize the shuttle to perform this function, it being understood that the term "shuttle" as here used and as hereafter used in the claims is intended to include a hook or other loop taking device by which the

locking thread is passed through the loops of needle thread.

The several features of the present invention will be clearly understood from an inspection of the accompanying drawings, illustrating the preferred embodiment of the invention, in connection with the following description.

Referring to the drawings Fig. 1 is a view in side elevation of a lockstitch McKay shoe sewing machine embodying the present invention; Fig. 2 is a detail view showing in front elevation and partially in section certain parts of the machine and illustrating particularly the mechanism connected with the presser foot for varying the operation of the take-up; Fig. 3 is a detail sectional plan view of the take-up mechanism; Fig. 4 is a view in side elevation, partly in section, of the mechanism illustrated in Fig. 3; and Figs. 5, 6 and 7 are diagrammatic views illustrating the operation of the thread handling devices of the machine in forming and setting a stitch.

The machine illustrated in the drawings is the same in the general construction and arrangement of its parts as the lockstitch McKay shoe sewing machine illustrated in the patent to Goddard and Jerram, No. 1,353,827, dated September 28, 1920. Reference to this patent may be had for a full disclosure of details of constructions not illustrated in the drawings of the present application.

Referring to Figs. 1 and 2 the straight hook needle of the machine is indicated at 9, the shuttle at 10, the presser foot at 11, the feed point at 12, the shoe supporting horn at 13, and the whirl which lays the thread in the hook of the needle at 14. The needle, presser foot and feed point are actuated from a horizontal cam shaft driven through bevelled gears 15 and 16 from a vertical shaft 17, and the shuttle and whirl are driven through connections from the vertical shaft 17, as in the machine of the Goddard and Jerram patent.

The thread lock against which the stitch is set comprises a spring pressed plunger 18 mounted upon a lever 19 and a fixed clamping plate 20 mounted in a bracket 21 of the machine frame. The lever 19 carrying the plunger 18 is actuated from a cam groove in the barrel member 22 on the vertical shaft 17, the construction being such that the lever is actuated to open and close the thread lock during each cycle of operations of the machine.

To permit the needle to set the stitch, the illustrated machine is provided with a take-up mechanism which draws back through the work a portion of the needle loop which has been passed around the shuttle, leaving just enough thread in the loop projecting above the work to supply the needle with thread until it reaches the end of its retracting stroke. This take-up mechanism comprises

two take-up levers 23 and 24 provided respectively with a thread guiding roll 25 and with thread guiding rolls 26 and 27. These levers are acted upon by cam grooves in the barrel member 22 and the construction is such that during each cycle of operations of the machine the forward ends of the levers are caused to approach and separate. The thread passes from the supply through the thread lock, around a guide roll 29 mounted on the bracket 21 and then around the rolls on the take-up levers and to the work. As the front ends of the levers approach each other thread is given up to the retracting needle and to the shuttle and as the front ends of the levers separate, the thread lock being closed at this time, thread from the needle loop which has been passed about the shuttle is drawn back through the work.

To compensate for different thicknesses of work, means are provided for varying the action of the take-up as the work varies in thickness. This means comprises a guide roll 30 at the upper end of a bar 31 arranged to slide vertically in the bracket 21. The roll 30 is so positioned in the machine that as the take-up lever 24 approaches its lower limit the thread extending between the rolls 26 and 27 is engaged by the roll 30 and deflected upwardly between the rolls. The lower end of the bar 31 is connected to the presser foot bar of the machine through a lever 33, a connecting rod 34 and a lever 35, so that as the work varies in thickness the position of the roll 30 is correspondingly changed and thereby an amount of thread is pulled back through the work by the take-up varying with the thickness of the work.

The operation of the thread handling devices of the machine has already been indicated but may be briefly stated as follows: At the end of the take-up action of the take-up the parts are in the position illustrated in Fig. 5, the take-up levers being separated, the thread lock being closed and the needle being just about to enter the work on its downward stroke. As will be obvious from the figure, the needle loop which has been passed around the shuttle has been pulled back through the work until just enough thread remains in the loop on the needle side of the work to furnish one side of the next needle loop during the retracting stroke of the needle. This length of loop remaining above the work at the end of the take-up action is constant for all thicknesses of work, the variation in the action of the take-up mechanism to produce this result being effected by a variation in the thickness of the work as has been described. After the needle passes through the work the thread is laid in its hook and the needle retracts to the limit of its upward stroke. During this action of the needle the thread lock remains closed and as the needle reaches the limit of its upward stroke, as indicated in Fig. 6, a stitch

setting strain is exerted on the thread so that the stitch is set by the needle against the thread lock, the shuttle thread being pulled into the work by the needle thread a pre-determined and exact distance. The thread lock is now opened, the needle loop is taken by the shuttle, and as it passes over the shuttle, thread for the next stitch is pulled from the supply. After the loop passes over the top of the shuttle the thread lock is closed and the take-up levers are actuated to shorten the loop, the parts then being again in the position indicated in Fig. 5.

The nature and scope of the present invention having been indicated and the preferred embodiment of the invention having been specifically described, what is claimed is:—

1. A lockstitch sewing machine having, in combination, stitch forming and setting devices including a hook needle acting during its retracting stroke to set the stitch, a shuttle, a take-up, a thread lock against which the stitch is set, means for actuating the parts, and means controlled by the thickness of the work for determining the position of the lock of the stitch in the work.

2. A lockstitch sewing machine having, in combination, stitch forming and setting devices including a hook needle acting during its retracting stroke to set the stitch, a shuttle, a take-up, a thread lock against which the stitch is set, means for actuating the parts, and means for varying the action of the take-up to compensate for different thicknesses of work.

3. A lockstitch sewing machine having, in combination, stitch forming and setting devices including a hook needle acting during its retracting stroke to set the stitch, a shuttle acting to pull off thread for the next stitch, a take-up, a thread lock against which the stitch is set, and means for varying the action of the take-up to compensate for different thicknesses of work.

4. A lockstitch sewing machine having, in combination, stitch forming and setting devices including a hook needle acting during its retracting stroke to set the stitch, a shuttle, a take-up, a thread lock against which the stitch is set, means for actuating the parts, and means controlled by the thickness of the work for maintaining constant the length of the loop left on the needle side of the work by the take-up.

5. A lockstitch sewing machine having, in combination, stitch forming devices including a hook needle acting during its retracting stroke to draw thread from the preceding needle loop, a shuttle acting to pull off thread for the next stitch, a take-up acting to pull the needle loop from the shuttle partially back through the work, and a thread lock against which the stitch is set.

6. A lockstitch sewing machine having, in combination, stitch forming and setting de-

vices including a hook needle acting during its retracting stroke to set the stitch, a shuttle acting to pull off thread for the next stitch, a take-up, a thread lock against which the stitch is set, and means for actuating the parts.

7. A lockstitch sewing machine having, in combination, stitch forming and setting devices including a hook needle acting at the limit of its retracting stroke to set the stitch, a shuttle, a take-up, a thread lock against which the stitch is set, and means for actuating the parts.

8. A lockstitch sewing machine having, in combination, stitch forming devices including a hook needle acting during its retracting stroke to draw thread from the preceding needle loop, a shuttle, take-up mechanism other than the needle or shuttle acting to pull the loop of needle thread from the shuttle part way down to the work, and means for adjusting the take-up mechanism to vary its taking up action to leave substantially the same amount of thread projecting from work of different thicknesses.
